US00D870710S

(12) **United States Design Patent** (10) Patent No.: **US D870,710 S**
(45) Date of Patent: **** Dec. 24, 2019**

(54) **EARPHONE**

(71) Applicant: **Guangzhou Lanshidun Electronic Limited Company**, Guangzhou (CN)

(72) Inventor: **Hejin Cai**, Guangzhou (CN)

(73) Assignee: **Guangzhou Lanshidun Electronic Limited Company**, Guangzhou (CN)

(**) Term: **15 Years**

(21) Appl. No.: **29/660,069**

(22) Filed: **Aug. 16, 2018**

(51) LOC (12) Cl. **14-01**

(52) U.S. Cl.

USPC **D14/223**

(58) **Field of Classification Search**

USPC D14/205, 223; D24/174

CPC H04R 1/10; H04R 25/00

See application file for complete search history.
